CLAIM

The ornamental design for a shutter door, as shown and described.

DESCRIPTION

FIG. 1 is a front perspective view of a shutter door showing my new design;

FIG. 2 is a rear perspective view thereof;

FIG. 3 is a left perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

(Continued)

Broken lines in the drawings depict portions of the shutter door that form no part of the claimed design.

1 Claim, 7 Drawing Sheets
